 **α -HALOSULFONIUM YLIDS AND
 α -HALOSULFONIUM SALTS**

Kenneth Wayne Ratts, Creve Coeur, Mo., assignor to Monsanto Company, St. Louis, Missouri, a corporation of Delaware
No Drawing. Filed May 11, 1966, Ser. No. 549,162
15 Claims. (Cl. 260—592)

ABSTRACT OF THE DISCLOSURE

The α -halosulfonium compounds of this invention are represented by a formula selected from the group consisting of

and

wherein R and R¹ are each selected from the group consisting of hydrogen, alkyl of not more than 12 carbon atoms and haloalkyl of not more than 12 carbon atoms containing 1, 2 or 3 halogen atoms, X is halogen (Cl, Br and I), R² is selected from the group consisting of halogen (Cl, Br, F and I) and alkyl of not more than 4 carbon atoms, R³ is selected from the group consisting of NO₂ and alkoxy of not more than 4 carbon atoms, R⁴ is phenyl, a is an integer from 0 to 5 inclusive, b is an integer from 0 to 2 inclusive and c is an integer from 0 to 1.

The α -halosulfonium compounds of this invention are represented by a formula selected from the group consisting of

and

wherein R and R¹ are each selected from the group consisting of hydrogen, alkyl of not more than 12 carbon atoms and haloalkyl of not more than 12 carbon atoms containing 1, 2 or 3 halogen atoms, X is halogen (Cl, Br and I), R² is selected from the group consisting of halogen (Cl, Br, F and I) and alkyl of not more than 4 carbon atoms, R³ is selected from the group consisting of NO₂ and alkoxy of not more than 4 carbon atoms, R⁴ is phenyl, a is an integer from 0 to 5 inclusive, b is an integer from 0 to 2 inclusive and c is an integer from 0 to 1.

This invention relates to α -halosulfonium ylids and α -halosulfonium salts, and to processes of making them. This invention further relates to fungicidal compositions and methods for the control of fungal organisms.

In the above formula, R and R¹ can be hydrogen, alkyl such as methyl, ethyl, n-propyl, isopropyl, n-butyl, sec-butyl, isobutyl, tert-butyl, amyl, hexyl, heptyl, octyl, nonyl, decyl, dodecyl, and the various homologues and isomers of alkyl having from 1 to 12 carbon atoms and haloalkyl such as chloromethyl, iodomethyl, bromomethyl, fluoromethyl, chloroethyl, iodoethyl, bromoethyl, fluoroethyl, trichloromethyl, diiodoethyl, tribromoethyl, trifluoromethyl, dichloroethyl, chloro-n-propyl, bromo-n-propyl, iodoisopropyl, bromo-n-butyl, bromo-tert-butyl, 1,3,3-trichlorobutyl, 1,3,3-tribromobutyl, chloropentyl, bromopentyl, 2,3-dichloropentyl, 3,3-dibromopentyl, chlorohexyl, bromohexyl, 2,4-dichlorohexyl, 1,3-dibromohexyl, 1,3,4-trichlorohexyl, chloroheptyl bromoheptyl, fluoroheptyl, 1,3-dichloroheptyl, 1,4,4-trichloroheptyl, 2,4-di(chloromethyl)heptyl, chlorooctyl, bromooctyl, iodoctyl, 2,4-di(chloromethyl)hexyl, 2,4-dichlorooctyl, 2,4,4-tri(chloromethyl)pentyl, 1,3,5-tribromoocetyl and the halogenated straight and branched chain nonyl, decyl, undecyl and dodecyl. In the above formulae R and R¹ are preferably hydrogen, lower alkyl (1 to 4 carbon atoms) or lower haloalkyl (1 to 4 carbon atoms).

In the above formulae R² as alkyl can be the alkyl disclosed above for R and R¹ of not more than 4 carbon atoms. As alkoxy, R³ can be methoxy, ethoxy, n-propoxy, isopropoxy, n-butoxy, sec-butoxy, isobutoxy and tert-butoxy.

The α -halosulfonium salts of this invention are prepared by a process which comprises halogenation of a sulfonium ylid in accordance with the following representative synthesis

wherein R, R¹, R², R³, R⁴, X, a, b and c are as defined above.

Halogenation in accordance with this invention is carried out by admixing substantially equimolar amounts of reactants in the presence of an inert organic medium at room temperature, i.e. about 20° C. to 25° C. However, higher or lower temperatures can be employed, the temperature not being critical.

Suitable inert organic media which can be used in the preparation of the α -halosulfonium salts of this invention include by way of example hydrocarbons such as benzene, toluene, xylene, cyclohexane, methylcyclohexane, n-heptane, n-hexane and the like; ethers such as isopropyl ether, n-butyl ether, 1,4-dioxane, isobutyl ether, diethyl ether and the like; aliphatic and cycloaliphatic ketones such as methyl isopropyl ketone, methyl isobutyl ketone, methyl isoamyl ketone, diisopropyl ketone, cyclohexanone and the like; and organic halides such as carbon tetrachloride, n-butyl chloride, ethylene dichloride, and the like.

The α -halosulfonium ylids of the present invention are prepared by a process which comprises reacting an α -halosulfonium salt of the formula

wherein R, R¹, R², R³, R⁴, X, a, b and c are as defined above with a substantially equimolar amount of an alkali metal hydride such as sodium hydride under substantially anhydrous conditions in the presence of an inert organic media until a substantially equimolar amount of hydrogen has evolved. The process is suitably carried out at room temperature, i.e. about 20° C. to 25° C. However, higher or lower temperatures can be used, the temperature not being critical. Inert organic media for use in this invention include, for example, tetrahydrofuran, diglyme, diethylether and the like.

Pressure is not a critical factor in either of the above processes of this invention. Pressure both above and below atmospheric can be employed although atmospheric pressure is preferred for convenience.

The separation of the resulting α -halosulfonium ylids or α -halosulfonium salts from the reaction mixture is readily accomplished. The α -halosulfonium salts are separated from the reaction mixtures by filtration or decantation. In some cases it may be necessary to remove the solvent from the resulting filtrate by stripping or distillation, preferably low temperature vacuum distillation, to recover all of the product salts. The α -halosulfonium ylids are separated from the reaction mixture by removing the alkali metal halide salt formed during the reaction by filtration and the solvent from the filtrate by stripping or distillation. The product ylids and salts can be purified by any of the conventional means well known in the art, e.g. selective extraction, recrystallization or a combination of these methods.

The α -halosulfonium ylids and α -halosulfonium salts of this invention are crystalline solid materials which are insoluble in water but somewhat soluble in many organic solvents, for example, alcohols, ketones, hydrocarbons such as benzene, toluene, xylene and the like and chlorohydrocarbons such as chlorobenzene, carbon tetrachloride and the like.

The following examples illustrate the invention. Parts and percent are by weight unless otherwise indicated.

Example 1

To a suitable reaction vessel charged with about 4.5 parts of dimethylsulfonium phenacylide and 50 parts of trichloromethane is added 4.0 parts of bromine with stirring at room temperature (about 20° C.). At the end of the bromine addition, the reaction mixture is filtered and the solids (4.35 parts) are crystallized from methyl alcohol to give (α -bromophenacyl) dimethylsulfonium bromide, M.P. 124-125° C.

Calcd. for C₁₀H₁₂Br₂SO: C, 35.31; H, 3.56; Br, 47.00; S, 9.43. Found: C, 35.23; H, 3.38; Br, 47.05; S, 9.61.

Following substantially the same procedure as in the foregoing example the following α -halosulfonium salts of this invention are prepared.

Example

- 2 (α -chlorophenacyl) dimethylsulfonium chloride
- 3 (α -iodophenacyl) dimethylsulfonium iodide
- 4 (α -chloro-4-chlorophenacyl) dimethylsulfonium chloride
- 5 (α -chloro-2,4-dichlorophenacyl) dimethylsulfonium chloride
- 6 (α -chloro-2,4,6-trichlorophenacyl) dimethylsulfonium chloride
- 7 (α -chloro-4-methylphenacyl) dimethylsulfonium chloride
- 8 (α -chloro-4-tert-butylphenacyl) dimethylsulfonium chloride
- 9 (α -chloro-2,4-dimethylphenacyl) dimethylsulfonium chloride
- 10 (α -chloro-2,4,6-trimethylphenacyl) dimethylsulfonium chloride
- 11 (α -chloro-2,5-diethylphenacyl) dimethylsulfonium chloride
- 12 (α -chloro-2,6-di-tert-butylphenacyl) dimethylsulfonium chloride

- 13 (α -chloro-4-bromophenacyl) dimethylsulfonium chloride
- 14 (α -chloro-3,5-dibromophenacyl) dimethylsulfonium chloride
- 15 (α -chloro-2-iodophenacyl) dimethylsulfonium chloride
- 16 (α -chloro-2,6-difluorophenacyl) dimethylsulfonium chloride
- 17 (α -chloro-2,5-dimethylphenacyl) dimethylsulfonium chloride
- 18 (α -chloro-3,5-dimethylphenacyl) dimethylsulfonium chloride
- 19 (α -chloro-2,3,4,5,6-pentachlorophenacyl) dimethylsulfonium chloride
- 20 (α -chloro-4-nitrophenacyl) dimethylsulfonium chloride
- 21 (α -chloro-2,4-dinitrophenacyl) dimethylsulfonium chloride
- 22 (α -chloro-4-methoxyphenacyl) dimethylsulfonium chloride
- 23 (α -chloro-2,4-dimethoxyphenacyl) dimethylsulfonium chloride
- 24 (α -chloro-2,5-dimethoxyphenacyl) dimethylsulfonium chloride
- 25 (α -chloro-4-n-butoxyphenacyl) dimethylsulfonium chloride
- 26 (α -chloro-4-phenylphenacyl) dimethylsulfonium chloride
- 27 (α -chloro-2-methyl-4-nitrophenacyl) dimethylsulfonium chloride
- 28 (α -chloro-2-methoxy-4-chlorophenacyl) dimethylsulfonium chloride
- 29 (α -fluoro-2-methyl-4-methoxyphenacyl) dimethylsulfonium chloride
- 30 (α -bromophenacyl) diethylsulfonium bromide
- 31 (α -bromophenacyl) di(n-butyl)sulfonium bromide
- 32 (α -bromophenacyl) di(n-octyl) sulfonium bromide
- 33 (α -bromophenacyl) di(2-chloroethyl)sulfonium bromide
- 34 (α -iodophenacyl) di(3-chlorobutyl)sulfonium bromide
- 35 (α -chlorophenacyl) di(n-dodecyl)sulfonium chloride
- 36 (α -chloro-4-chlorophenacyl) di(4,4-dichloropentyl)sulfonium chloride
- 37 (α -chlorophenacyl) di(2,2,4-tribromobutyl)sulfonium chloride
- 38 (α -chlorophenacyl) di(2-fluoropentyl)sulfonium chloride
- 39 (α -chlorophenacyl) di(2-iodoethyl)sulfonium chloride
- 40 (α -bromo-2,4-dimethylphenacyl) diethylsulfonium bromide

Example 41

A suitable reaction vessel is charged with about 750 parts of tetrahydrofuran, 17.0 parts of (α -bromophenyl) dimethylsulfonium bromide and 2.3 parts of sodium hydride. The reaction mixture is stirred at room temperature until the evolution of hydrogen is substantially complete. The reaction mixture is filtered to remove the solids which are then extracted with methylene chloride. The methylene chloride extract is concentrated by evaporation to give 10.5 parts of dimethylsulfonium α -bromophenacylide, M.P. 129-132° C. The filtrate from the reaction mixture is evaporated under vacuum to give an additional 1.6 parts of dimethylsulfonium α -bromophenacylide.

Calcd. for C₁₀H₁₁BrOS: C, 46.34; H, 4.28; Br, 30.84; O, 6.17; S, 12.37. Found: C, 46.12; H, 4.28; Br, 30.70; O, 6.89; S, 12.11.

Following substantially the same procedure as in Example 41 above the following α -halosulfonium ylids of this invention are prepared.

Example

- 42 dimethylsulfonium α -chlorophenacylide
- 43 dimethylsulfonium α -iodophenacylide

- 44 dimethylsulfonium α -bromo-4-chlorophenacylide
 45 dimethylsulfonium α -bromo-2,4-dichlorophenacylide
 46 dimethylsulfonium α -bromo-2,4,6'-trichlorophenacylide
 47 dimethylsulfonium α -chloro-4-methylphenacylide
 48 dimethylsulfonium α -chloro-4-tert-butylphenacylide
 49 dimethylsulfonium α -chloro-2,4-dimethylphenacylide
 50 dimethylsulfonium α -chloro-2,4,6'-trimethylphenacylide
 51 dimethylsulfonium α -chloro-2,5-diethylphenacylide
 52 dimethylsulfonium α -chloro-2,6-di(tert-butyl)phenacylide
 53 dimethylsulfonium α -bromo-4-bromophenacylide
 54 dimethylsulfonium α -bromo-3,5-dibromophenacylide
 55 dimethylsulfonium α -bromo-2-iodophenacylide
 56 dimethylsulfonium α -bromo-2,6-difluorophenacylide
 57 dimethylsulfonium α -chloro-2,5-dimethylphenacylide
 58 dimethylsulfonium α -chloro-3,5-dimethylphenacylide
 59 dimethylsulfonium α -chloro-2,3,4,5,6-pentachlorophenacylide
 60 dimethylsulfonium α -bromo-4-nitrophenacylide
 61 dimethylsulfonium α -bromo-2,4-dinitrophenacylide
 62 dimethylsulfonium α -bromo-4-methoxyphenacylide
 63 dimethylsulfonium α -bromo-2,4-dimethoxyphenacylide
 64 dimethylsulfonium α -bromo-2,5-dimethoxyphenacylide
 65 dimethylsulfonium α -chloro-4-n-butoxyphenacylide
 66 dimethylsulfonium α -chloro-4-phenylphenacylide
 67 dimethylsulfonium α -chloro-2-methyl-4-nitrophenacylide
 68 dimethylsulfonium α -chloro-2-methoxy-4-chlorophenacylide
 69 dimethylsulfonium α -chloro-2-methyl-4-methoxyphenacylide
 70 diethylsulfonium α -bromophenacylide
 71 di(n-butyl)sulfonium α -bromophenacylide
 72 di(n-octyl)sulfonium α -bromophenacylide
 73 di(2-chloroethyl)sulfonium α -bromophenacylide
 74 di(3-chlorobutyl)sulfonium α -bromophenacylide
 75 di(n-dodecyl)sulfonium α -bromophenacylide
 76 di(4,4-dichloropentyl)sulfonium α -chloro-4-chlorophenacylide
 77 di(2,2,4-tribromobutyl)sulfonium α -chlorophenacylide
 78 di(2-fluoropentyl)sulfonium α -chlorophenacylide
 79 di(2-iodoethyl)sulfonium α -chlorophenacylide
 80 diethylsulfonium α -bromo-2,4-dimethylphenacylide

The sulfonium ylids used as starting materials in the preparation of the α -halosulfonium salts of this invention and processes for making them are disclosed and claimed in application Ser. No. 549,166, now United States Patent No. 3,359,222, filed of even date herewith. Said process comprises reacting a sulfonium salt of the formula

wherein R, R¹, R², R³, R⁴, X, a, b and c are as defined above with a substantially equimolar amount of an alkaline material such as sodium hydride or sodium hydroxide in the presence of an inert liquid medium such as an aqueous medium or organic medium. Temperature is not critical and room temperature is usually employed.

The α -halosulfonium ylids and α -halosulfonium salts of this invention are useful for various purposes such as fire retardants, rust inhibitors, rust removers, tanning agents and water-insoluble dispersion agents, and as chemical intermediates for petroleum additives and agricultural chemicals. For example, the α -halosulfonium ylids and α -halosulfonium salts of this invention are useful as pesticides, particularly fungicides. In practicing the fungicidal methods of this invention, one or more of the present α -halosulfonium ylid or α -halosulfonium salts is applied to the fungal organisms or the material to be treated for the control of fungi in an amount sufficient

to exert fungicidal activity. The fungicidal sulfonium compounds of this invention are particularly effective when applied directly to the soil for control of soil borne fungal organisms. They are also effective in the treatment of plant life such as vegetables, ornamental plants and fruit-bearing trees; organic fibers and fabrics; leather; paints and lubricating oils and various cellulosic materials such as wood. In application to soil and plants, fungicidal control is obtained in most instances by the application of from about 0.01 pound to about 25 pounds of active ingredient per acre. The preferred amount is determined by and dependent upon the particular fungicidal compound selected, the method of application, and in the case of application to plant life, the state and condition of growth and the climatic conditions.

The fungicidal activity of the α -halosulfonium compounds of the invention is demonstrated as follows.

An intimate mixture of 2 volumes of yellow corn meal and 3 volumes of white sand is infested with a particular pathogen (below itemized) and incubated for two weeks at 20° C. Then one volume of this infested mixture is blended uniformly with 3 volumes of a good grade of top soil which had been sterilized. To accomplish complete blending the composite of soil and infested mixture is passed through a No. 8 screen three times. A number of small cups are then tightly packed with 30 gram portions of the composite and the surface thereof leveled.

A sufficient amount of (α -iodophenacyl)dimethylsulfonium iodide is dissolved in acetone to make a 1% by weight solution which is then diluted with water to provide a formulation having a concentration of 0.1% by weight. To provide the desired concentration in the afore-described soil composite the following further dilutions with water are made:

35 Conc. desired in soil in p.p.m. ----- 30
 Ml. of 0.1% formulation ----- 1
 Ml. of water added to formulation ----- 3

The 4 ml. portions are drenched over the surface of the soil in each cup, care being taken to insure even distribution. The cups are then placed in a 100% humidity chamber at 70° F. for 44 hours. Upon removal from the chamber the amount of mycelial growth on the surface of the soil is noted and rated as follows:

45 1=no growth
 2=growth from corn meal only
 3=some growth in soil away from corn meal particles
 4=surface covered but little aerial growth
 5=growth equivalent to that on untreated soil.

50 The results obtained with (α -iodophenacyl) dimethylsulfonium iodide at a soil concentration of 30 p.p.m. are set forth below for each of the two identical fungal organisms:

55 Fungal organism:	Rating
Pythium ultimum -----	1
Rhizoctonia solani -----	1

60 The fungicidal compositions of this invention contain at least one active ingredient and a material referred to in the art as a fungicidal adjuvant in liquid or solid form. The fungicidal compositions are prepared by admixing the active ingredient with an adjuvant including diluents, extenders, carriers and conditioning agents to provide 65 compositions in the form of finely-divided particulate solids, granules, pellets, solutions, aerosols and aqueous dispersions or emulsions. Thus the active ingredient can be used with an adjuvant such as a finely-divided particulate solid, a liquid of organic, water, a wetting agent, dispersing agent, an emulsifying agent or any suitable combination of these.

70 Typical finely-divided solid carrier and extenders which can be used in the fungicidal compositions of this invention include, for example, the talcs, clays, pumice, silica, diatomaceous earth, charcoal, quartz, Fuller's

earth salt, sulfur, powdered cork, powdered wood, walnut flour, chalk, tobacco dust, volcanic ash, and the like. Typical liquid diluents include, for example, water, kerosene, Stoddard solvent, hexane, benzene, toluene, acetone, ethylene dichloride, xylene, alcohols, diesel oil, glycols and the like. Typical diluents for aerosols include, for example, Freons such as dichlorofluoromethane, trichlorofluoromethane, and the like.

The fungicidal compositions of this invention, particularly liquids and wettable particles, usually contain as a conditioning agent one or more surface-active agents in amounts sufficient to render a given composition readily dispersible in water or in oil. By the term "surface-active agent" it is understood that wetting agents, dispersing agents, suspending agents, emulsifying agents and the like are included therein.

The surface-active agents employed can be of the anionic, cationic or nonionic type. They include, for example, sodium oleate, sulfonated petroleum oils, alkyl aryl sulfonates, sodium lauryl sulfate, polyethylene oxides, lignin sulfonates, and other surface-active agents.

The fungicidal compositions of this invention generally contain from about 0.005% to about 95% by weight of the active fungicidal ingredient.

The fungicidal compounds of the present invention can be employed in combination with other fungicides to give compositions that have broad spectrum fungicidal activity. In these mixtures, the auxiliary fungicidally active materials can be present in any desired amount, ordinarily from about 0.1 to about 20 parts by weight per 1 part by weight of a compound of the present invention. In some instances it may even be desirable to employ two or more auxiliary fungicides.

Typical of the auxiliary fungicides that can be employed in combination with the compounds of the present invention are the following:

N-trichloro-methylthio-4-cyclohexene-1,2-dicarboximide
Tetramethylthiuram disulfide
Manganese ethylene-bis-dithiocarbamate
Ferric dimethyl dithiocarbamate
Zinc ethylene-bis-dithiocarbamate
Zinc dimethyl dithiocarbamate
Tetra copper calcium oxychloride
Tetrachloro-p-benzoquinone
2,3-dichloro-1,4-naphthoquinone
2-dichloro-6-(o-chloroanilino)triazine
Ethylene thiuram monosulfide
2-heptadecyl glyxalidine acetate
Ferric dimethyl dithiocarbamate plus 2-mercaptopbenzo-thiazole
Manganese dimethyl dithiocarbamate plus 2-mercaptopbenzo-thiazole
Copper dihydrazinium sulfate
Copper-S-quinolinolate
Cycloheximide
Terramycin
Streptomycin

When operating in accordance with the present invention, the α -halosulfonium compounds or a composition containing them can be applied to the fungal organisms to be controlled, or to their habitats in any convenient fashion, e.g., by means of hand dusters or sprayers. Applications to the above-ground portions of plants conveniently can be carried out with powder dusters, boom sprayers and spray dusters. In foliar applications, the employed compositions should not contain any appreciable amount of phytotoxic diluents. In large scale operations, dusts or low volume sprays may be applied from airplanes.

The term "fungicidal composition" as used herein and in the appended claims is intended to mean not only compositions in a suitable form for application but also con-

centrated compositions which require dilution or extension with a suitable quantity of liquid or solid adjuvant prior to application.

The emodiments of the invention in which an exclusive property or privilege is claimed are defined as follows:

1. Compound having a formula selected from the group consisting of

10 (a)

15 and

(b)

wherein R and R¹ are each selected from the group consisting of hydrogen, alkyl of not more than 12 carbon atoms and haloalkyl of not more than 12 carbon atoms containing from 1 to 3 halogen atoms, X is selected from the group consisting of Cl, Br and I, R² is selected from the group consisting of halogen and alkyl of not more than 4 carbon atoms, R³ is selected from the group consisting of NO₂ and alkoxy of not more than 4 carbon atoms, R⁴ is phenyl, a is an integer from 0 to 5 inclusive, b is an integer from 0 to 2 inclusive and c is an integer from 0 to 1 inclusive.

2. Compound of claim 1 having the formula represented by (a).

3. Compound of claim 1 having the formula represented by (b).

4. Compound of claim 1 which is (α -bromophenacyl) dimethylsulfonium bromide.

5. Compound of claim 1 which is (α -chloro-2,4-dichlorophenacyl) dimethylsulfonium chloride.

6. Compound of claim 1 which is (α -chloro-2,4,6-trimethylphenacyl) dimethylsulfonium chloride.

7. Compound of claim 1 which is (α -chlorophenacyl) dimethylsulfonium chloride.

8. Compound of claim 1 which is (α -chlorophenacyl) diethylsulfonium chloride.

9. Compound of claim 1 which is (α -iodophenacyl) dimethylsulfonium iodide.

10. Compound of claim 1 which is dimethylsulfonium α -chlorophenacylide.

11. Compound of claim 1 which is dimethylsulfonium α -bromophenacylide.

12. Compound of claim 1 which is dimethylsulfonium α -iodophenacylide.

13. Process for the preparation of a compound of the formula

60

65

wherein R and R¹ are each selected from the group consisting of hydrogen, alkyl of not more than 12 carbon atoms and haloalkyl of not more than 12 carbon atoms containing from 1 to 3 halogen atoms, X is selected from the group consisting of Cl, Br and I, R² is selected from the group consisting of halogen and alkyl of not more than 4 carbon atoms, R³ is selected from the group consisting of NO₂ and alkoxy of not more than 4 carbon atoms, R⁴ is phenyl, a is an integer from 0 to 5 inclusive, b is an integer from 0 to 2 inclusive and c is an integer

70

from 0 to 1, which comprises reacting a sulfonium ylid of the formula

with a substantially equimolar amount of a halogen selected from the group consisting of chlorine, bromine and iodine, wherein R, R¹, R², R³, R⁴, a, b and c are as defined above.

14. Process for the preparation of a compound of the formula

wherein R and R¹ are each selected from the group consisting of hydrogen, alkyl of not more than 12 carbon atoms and haloalkyl of not more than 12 carbon atoms containing from 1 to 3 halogen atoms, X is selected from the group consisting of Cl, Br and I, R² is selected from the group consisting of halogen and alkyl of not more than 4 carbon atoms, R³ is selected from the group consisting of NO₂ and alkoxy of not more than 4 carbon atoms, R₄ is phenyl, a is an integer from 0 to 5 inclusive, b is an integer from 0 to 2 inclusive and c is an in-

teger from 0 to 1, which comprises reacting an α -halosulfonium salt of the formula

5

10

wherein R, R¹, R², R³, R⁴, X, a, b and c are as defined above, with a substantially equimolar amount of an alkali metal hydride in the presence of an inert organic medium until a substantially equimolar amount of hydrogen evolves.

15. Compound of claim 1 wherein a, b and c are 0.
